UNITED STATES PATENT OFFICE.

ARGYLE CAMPBELL, OF CHICAGO, ILLINOIS, ASSIGNOR TO ENTERPRISE RAILWAY EQUIPMENT COMPANY, OF CHICAGO, ILLINOIS, A CORPORATION OF ILLINOIS.

CAR-DOOR-OPERATING MECHANISM.

Original application filed December 27, 1921, Serial No. 525,105. Divided and this application filed July 10, 1922. Serial No. 573,848.

To all whom it may concern:

Be it known that I, ARGYLE CAMPBELL, a citizen of the United States, residing at Chicago, in the county of Cook and State of Illinois, have invented a certain new and useful Improvement in Car-Door-Operating Mechanism, of which the following is a full, clear, concise, and exact description, reference being had to the accompanying drawings, forming a part of this specification.

This invention relates to improvements in car door operating mechanism.

This application is a division of my co-pending application, Serial No. 525,105, filed December 27, 1921.

In certain types of dump cars, it is customary to employ deep-bellied side sills or girders, thus making it exceedingly difficult to employ any of the usual types of door mechanism satisfactorily on account of the inaccessibility of the parts.

One object of my invention is to provide a simple and efficient door lifting and locking arrangement for dump cars which is especially adapted for those types of cars having deep side sills and pivoted floor doors between the sills and wherein the mechanism must necessarily be operated at the side of the car.

In the drawings forming a part of this specification, Figure 1 is a vertical, longitudinal, sectional view of a portion of a dump car showing my improvements in connection therewith, the section being taken in a plane inside of the side wall and side sill of the car and looking toward the center sill of the car. Figure 2 is a top plan view of the construction shown in Figure 1 but with the fixed floor boards omitted and the doors indicated conventionally by dotted lines, in order to better illustrate the door operating mechanism and its relation to the parts of the car underframe. Figure 3 is a vertical, transverse, sectional view of the structure illustrated in Figures 1 and 2 and corresponding substantially to the broken section line 3-3 of Figure 2. And Figure 4 is a vertical, sectional view of the side sill of the car, corresponding substantially to the section line 4-4 of Figure 2 and showing, in edge elevation, the means for locking and releasing the door operating shaft.

In said drawings, the car is shown as provided with a deep-bellied side sill 10, built-up center sill 11, side wall 12, and pressed diaphragms or needle beams 13, 14, 15 and 16. In the particular type of car shown, eight pivoted floor doors would be employed, four on each side of the center sill, the four doors on one side being arranged in pairs separated by fixed floor sections. Only one pair of such doors is illustrated in the drawings, it being understood that there will be a corresponding pair transversely aligned therewith but on the opposite side of the center sill and that the operating mechanism which I have shown, is adapted for simultaneously operating four doors. The fixed floor sections are indicated at 17, 18 and 19, the fixed floor section 18 being intermediate the two pivoted doors 20 and 21, shown in the drawings. The floor section 18 bridges the space between the two relatively shallow needle beams 14 and 15, thus affording a suitable cover and protection for the operating shaft and other parts of the mechanism associated therewith. The door 21 is pivotally supported by suitable brackets 22 secured to the deep needle beam 13 and the door 20 is similarly supported by brackets 22 secured to the shallow needle beam 16. It will be noted that the doors 20 and 21 are adapted to swing about axes extending transversely of the car and that the free edges of the doors are extended toward each other and engage under floor plates 23-23 secured to the edges of the fixed floor section 18.

In carrying out my invention, I employ a transversely extending operating shaft 24 which is mounted in suitable bearings carried by the side sill 10 and center sill 11, it being understood that the shaft 24 extends from side to side of the car. On at least one side of the car, the shaft 24 is extended through the side sill and provided with a square or other non-circular end 25 by which it may be rotated by means of a claw bar or other suitable tool. For each pair of doors 20 and 21, the shaft is provided with a pair of chain or cable winding drums 26-26, the drums being rigidly secured to the shaft. Each of said drums is provided with right and left helical grooves 27 to accommodate the oppositely extending cables or chains in

dicated conventionally at 28-28 in Figure 1.

Each chain or cable 28 extends over a sheave wheel 29 rotatably supported on a heavy pivot pin 30 mounted in a pair of flanges 31-31 formed integral with a bracket 32 secured to a needle beam 14. As clearly shown in Figure 3, the flanges 31 of each bracket 32 are curved and flared toward the winding drum so as to facilitate the passage of the chain or cable through the bracket. Opposite each sheave wheel 29 the bracket is formed with a vertically elongated opening 33 which alines with a corresponding opening 34, cut in the web of the needle beam. It will be noted that the securing flanges of the brackets 32 reinforce the needle beams around the openings thereof and thus compensate for the metal removed.

The ends of the chains or cables 28 are attached to eye-bolts 35 which are horizontally adjustably mounted in anchor castings 36 secured in line therewith to the under sides of the doors. Each of said anchor castings 36 is provided with a bell mouth 37 through which the cable or chain passes.

By rotating the shaft in a clockwise direction, as viewed in Figure 1, the chains or cables from all four doors will be simultaneously and uniformly wound around the respective drums, thus elevating the doors to closed position. The doors will be held in closed position so long as the operating shaft is prevented against rotation in a counter-clockwise direction. As hereinbefore noted, the floor section 18 covers and protects the shaft, drums, flexible connections and also the sheave wheels 29 and brackets are amply protected against injury during discharge of the load.

The mechanism for locking the shaft 24 in fixed position may be of any well known construction, and may have associated therewith the locking cam and safety device disclosed in my co-pending application referred to. As the specific construction of these elements does not form a part of the present invention, a detailed showing and description of the same is not deemed necessary, said elements being fully disclosed in my co-pending application referred to.

As herein shown, in Figures 2 and 4, to lock the operating shaft, the latter has secured thereto outside of the side sill 10, a ratchet wheel 38. The bearing for this end of the shaft is formed on a reinforcing casting 40 which is secured to the inner side of the side sill 10, as shown in Figure 4. Cooperable with the ratchet wheel 38 is a latch lever designated generally by the reference A. Said lever A is pivoted at its upper end on the pivot bolt 41, said bolt 41 being carried at its inner end by said plate 40 and at its outer end by an outer cover

plate 42 which is held spaced from the side sill 10. Near its point of pivotal support, the latch lever A is formed with a pawl shoulder adapted to engage with the teeth of the ratchet wheel 38 in such a manner as to prevent the latter from rotating counter-clockwise as shown in Figure 1. At its lower end, the lever A is formed with a suitable handle 44.

The lever A is held in locked relation with the ratchet wheel 38 by a cam plate 51 pivotally supported as indicated at 52 between the cover plate 42 and the side sill 10. Said cam plate 51 cooperates with a curved cam surface formed on the upper end of the lever A.

I have herein shown and described what I now consider the preferred manner of carrying out the invention but the same is merely illustrative and I contemplate all changes and modifications that come within the scope of the claims appended hereto.

I claim:

1. In a dump car, the combination with a pair of oppositely swinging pivoted floor doors separated by an intermediate fixed floor section, said doors having their pivots extending transversely of the car; of an operating shaft located beneath said floor section and on a level below the plane of the doors when the latter are in closed position, said shaft extending parallel to the pivotal axes of the doors; and oppositely extending flexible connections from said shaft to both doors.

2. In a dump car having oppositely swinging transversely pivoted floor doors separated by an intermediate fixed floor section, the combination with an operating shaft located beneath said floor section, said shaft having a plurality of winding drums thereon, each drum having right and left helical grooves, said shaft extending parallel to the pivotal axes of the doors; of oppositely extending flexible connections attached to said drums at one set of ends and at their other set of ends to the doors.

3. In a dump car having a deep side sill, transverse needle beams, a pair of oppositely swinging pivoted floor doors and a fixed floor section intermediate the doors, said fixed floor section extending between two of the needle beams; the combination with an operating shaft located beneath said fixed floor section and extending parallel to the pivotal axes of the doors and having one end projected through said side sill; of sheave wheels supported on said two needle beams; and oppositely extending flexible connections from said shaft to said doors passing over said sheave wheels and through openings in said needle beams.

4. In a dump car having a deep side sill, transverse needle beams, a pair of oppositely swinging pivoted floor doors and a fixed

floor section intermediate the doors, said fixed floor section extending between two of the needle beams; the combination with an operating shaft located beneath said fixed 5 floor section and extending parallel to the pivotal axes of the doors and having one end projected through said side sill; of sheave wheels supported on said two needle beams; and oppositely extending flexible 10 connections from said shaft to said doors passing over said sheave wheels and through openings in said needle beams.

In witness that I claim the foregoing I have hereunto subscribed my name this 24th day of June 1922.

ARGYLE CAMPBELL.
